Patented Dec. 23, 1924.

UNITED STATES PATENT OFFICE.

BORRE H. BORRESON, OF ST. PAUL, MINNESOTA.

CERTIFICATE OR TAG HOLDER.

Application filed June 24, 1922. Serial No. 570,690.

To all whom it may concern:

Be it known that I, BORRE H. BORRESON, a citizen of the United States, resident of St. Paul, county of Ramsey, State of Minnesota, have invented certain new and useful Improvements in Certificate or Tag Holders, of which the following is a specification.

The object of my invention is to provide improved means for fastening the tag or a card, such as a certificate of registration, to the wind shield of a vehicle, where it can be easily seen and inspected but can not be removed without detection.

A further object is to provide a holder of simple inexpensive construction which will securely hold the tag or certificate and will, at the same time, present a neat ornamental appearance on the car.

A further object is to provide a holder which can be easily and quickly removed from the shield to expose the glass for washing purposes.

Other objects of the invention will appear from the following detailed description.

The invention consists generally in various constructions and combinations, all as hereinafter described and particularly pointed out in the claims.

In the accompanying drawings forming part of this specification,

Figure 1 is a front view of a portion of the forward end of an automobile, showing the application of my invention to the wind shield,

Figure 2 is an enlarged detail view, looking at the opposite side of the shield,

Figure 3 is a vertical sectional view through the shield, showing the manner of mounting the certificate or card holder thereon,

Figure 4 is a sectional view on the line 4-4 of Figure 2,

Figure 5 is an enlarged detail view of a portion of the holder,

Figure 6 is a view corresponding to Figure 2, showing a modified means for fastening the card or tag holder on the wind shield,

Figure 7 is a detail view of the holder removed from the shield,

Figure 8 is a face view of the holder,

Figure 9 is a detail view, showing a modified means for supporting the tag or certificate holder on the shield.

In the drawing, 2 represents the lower portion or section of a vehicle wind shield.

3 is a holder having a recess 4 therein to receive the card or certificate and a seat 5 for the transparent plate 6 placed thereon and flanged edges 7 which are adapted to be rolled over upon the transparent plate to hold it in place and cover and protect the registration certificate or card 6^a that may be placed in the holder.

I designate the card by reference numeral 6^a and, as shown in Figure 8, notches or openings 6^b are provided, through which the identification number and the name of the State impressed in the back of the holder will be plainly visible. The corresponding number will appear on the card. Instead of having these notches in the edges of the card, I may provide openings through the middle portion thereof. This, however, is an obvious modification and I have not thought it necessary to illustrate the same herein, the purpose being precisely the same—that of allowing the figures or characters on the rear wall of the container to be plainly visible to a person standing in front of the holder.

At one end the holder has holes 8 therein to receive the ends 9 of a wire clip 10 that is folded to fit the edge of the shield and extend down on one side thereof opposite to the position of the holder. The frame of the shield at the opposite side has holes 11 therein and a cord or wire 12 is threaded through these holes and through holes 13 and sockets 14 in the holder, the ends of the cord or wire being passed through a loop 15 in the back plate of the holder and secured therein by closing the loops through which the cord passes. An impression of the State or other seal may then be made on the plate so that any attempt to remove the card or tamper with the holder will be instantly detected.

When the ends of the wire or cord are thus secured, the holder will be firmly held in position on the shield, the certificate or card therein being readable through the glass of the shield by a person standing in front of the car and the certificate and license number can be easily read and checked by any official desiring information as to the ownership of the car.

In Figures 6 and 7 I have shown a modified arrangement which consists in threading the cord or wire 17 through suitable holes in the rear wall of the holder and preventing removal of the cord or wire therefrom by a seal 18, then inserting the ends of the cord

or wire through the holes 11 in the frame of the shield and applying another seal 18^a to these ends to lock them therein.

In Figure 9 I have shown a loose wire clip 19 mounted on the edge of the shield and having a looped part 20 to extend down over the holder on the opposite side of the shield. At the other end of the holder the tag is sealed therein, but the holder is not connected with the frame of the shield.

The form of clip shown in Figure 9 allows the upper end of the holder to be instantly released so that it can swing down on its flexible connection at the lower end and expose the surface of the glass for washing or other purposes.

It will be understood that where the license number or other identifying mark is formed in the rear wall of the holder or container, it will be impossible to make any alterations in the mark without detection.

I claim as my invention:

1. The combination, with a wind shield, of a card or certificate holder arranged to fit against the face of the shield on one side and having means for engaging one edge of the shield, and a sealing means connecting the opposite portion of said holder with said shield and preventing its removal therefrom without detection.

2. A card or certificate holder having means for mounting it upon a vehicle, and provided with a rear wall having identification marks thereon, and a card fitting within said holder in front of said wall, the identification marks on said wall being visible when the card is placed in said holder.

3. The combination, with a wind shield, of a card or certificate holder seated thereon with the face of the card or certificate readable through the glass of said shield, a clip at one end of said holder for engaging the edge of the shield, and flexible means connecting the other end of said holder with said shield.

4. The combination, with a wind shield, of a card or certificate holder seated thereon with the face of the card or certificate readable through the glass of said shield, means connecting one edge of the shield with said

holder and flexible means threaded through holes in said holder and in the frame of said shield and a sealing device for said flexible means.

5. The combination, with a wind shield, of a card or certificate holder seated thereon, a card arranged within said holder and visible to a person in front of the shield, said holder having means for mounting it on the shield, said card bearing the license number and the name of the State issuing it and having openings therein through which corresponding marks are visible on the rear wall of the holder.

6. A card or certificate holder, a card fitting within said holder, and bearing a license number and other identifying marks, the edge of said card having notches therein and the rear wall of said holder having marks and numbers thereon indicating the number of the license corresponding to the one on said card and the name of the State issuing said license, said marks being permanently formed in the wall of said holder.

7. The combination with a vehicle, of a card or certificate holder, means connecting one end of said holder with its support on said vehicle, flexible means connecting the other end of said holder with its support, and a sealing device for said flexible means.

8. The combination with a vehicle, of a card or certificate holder, means connecting one end of said holder with its support on said vehicle, flexible means connecting the other end of said holder with its support, and a sealing device for said flexible means, the rear wall of said holder having identification marks thereon, and said card having an opening through which said marks are visible.

9. A card or tag holder having a seat for a card bearing the license number and a transparent plate fitting over said card and through which the number thereon is visible, said holder having a surface that is visible through said transparent plate whereon a number or character is placed.

In witness whereof, I have hereunto set my hand this 16th day of June, 1922.

BORRE H. BORRESON.
